UNITED STATES PATENT OFFICE.

DANIEL WALLACE JONES, OF LANCASTER, VIRGINIA.

SAWMILL.

963,770.

Specification of Letters Patent. Patented July 12, 1910.

Application filed September 27, 1909. Serial No. 519,777.

To all whom it may concern:

Be it known that I, DANIEL WALLACE JONES, a citizen of the United States, and a resident of Lancaster, in the county of Lancaster and State of Virginia, have invented 5 certain new and useful Improvements in Sawmills, of which the following is a specification.

The invention relates to improvements in 10 saw-mills, and consists in the novel features hereinafter described, and particularly pointed out in the claims.

The invention pertains more particularly to the vertically and longitudinally adjustable dogs which are carried by the movable knees for holding the logs on the blocks preparatory to and during the sawing operation, and in accordance with my invention I provide the saw-mill knees with dogs and 20 coöperative mechanism which will prevent the dogs from getting into the plane of the saw and also at the proper time permit the dogs to move inwardly or in a direction from the saw without manual aid or automatically. 25

The objects of my invention are, among other purposes, to obviate all the accidents and loss which may occur from the movement of a dog into the path of the saw, to 30 guard against the results of carelessness on the part of the sawyer with respect to the relation of the dog to the plane of the saw, to relieve the sawyer of the responsibility of determining when the dog is in such proximity to the plane of the saw as to require 35 its readjustment and to save the time of the sawyer in effecting a readjustment of the dog.

The invention will be fully understood 40 from the detailed description hereinafter presented, reference being had to the accompanying drawings, in which:

Figure 1 is an end elevation, partly in section and partly broken away, of a saw-mill 45 equipped with a dog and coöperating mechanism embodying my invention; Fig. 2 is a top view of a portion of the same; Fig. 3 is a reverse end elevation, partly broken away, of a portion of the mechanism shown in Fig. 1; Fig. 4 is an enlarged elevation, partly in section, of a portion of the mechanism shown 50 in Fig. 1, the box-like carrier which holds the dog and is mounted on the knee being in vertical section on the dotted line 4—4 of Fig. 6; Fig. 5 is an enlarged horizontal section 55 through the knee and dog-coöperating

mechanism on the dotted line 5—5 of Fig. 6; Fig. 6 is an edge view, partly broken away, of the knee with the dog and some of its mechanism shown in vertical section on the dotted line 6—6 of Fig. 7; Fig. 7 is an enlarged elevation of a portion of the mechanism shown in Fig. 1, the dog being shown in its retracted position; Fig. 8 is an end elevation of a portion of a saw-mill embodying a modified form or arrangement of my invention; Fig. 9 is a horizontal section of the same on the dotted line 9—9 of Fig. 8, and Fig. 10 is a horizontal section of the same on the dotted line 10—10 of Fig. 8. 70

In the drawings, referring to Figs. 1 to 7 inclusive, 10 designates one of the usual blocks of a saw-mill on which the log 11 is supported and carried, 12 a portion of the customary carriage supporting said blocks, 75 13 the track-rails for the wheels of said carriage, 14 a knee slidably mounted on said block, 15 the dog to engage said log, and 16 the saw. The knee 14 will be of any suitable construction and at its lower end rests, 80 as usual, on the block 10 at opposite sides of a groove 17 (Fig. 2) therein provided to receive a rack-bar 18 which is rigid with the knee and engaged by a gear wheel 19 on a shaft 20 carried by the block. The rack- 85 bar 18, gear wheel 19 and shaft 20 constitute the familiar mechanism employed in saw-mills for enabling the shifting of the knee 14 toward or from the plane of the saw 16 and therefore do not require detailed 90 description. 95

My invention relates to the dog 15 and its coöperating mechanism.

The dog 15 comprises an outer end prong 21 and a bar-like body 22, which, as more clearly shown in Fig. 4, is longitudinally slotted or bifurcated to form upper and lower arms 23, 24, respectively, the former having a series of transverse pin-holes 25 and the arm 24 a series of ratchet teeth 26. 100 The dog 15 is adjustably mounted in a box or frame 27 which is adjustable vertically on the knee 14. In the present instance the frame 27 is in the form of a rectangular box, and a vertical bar 28 offset from the knee 14, 105 passes through openings 29 in the top and bottom of said box and close to the back of the same (Figs. 5 and 6). The back of the box 27 is close between the bar 28 and knee 14 and the box is slideable vertically on said bar. The means for securing the box or frame 27 on the bar 28 may be an eccentric 110

30 pivotally secured within and to the box and operable by a handle-bar 31 extending outwardly through a slot 32 in the face of the box or frame and having a ball or weighted outer end 33 adapted to normally 5 keep the eccentric in locking engagement with the bar 28 and thereby lock the box or frame 27 thereon. By lifting the end 33 of the bar 31 the eccentric 30 will be released 10 from the bar 28, and then the box 27 may be moved vertically on said bar at will. When the box 27 has been placed in proper position on the bar 28 and the weighted end of the bar 31 is released the eccentric will 15 automatically engage the bar 28 and lock the box 27 thereon. The bar 31 may be used as a convenient handle in moving the box 27 vertically. The body 22 of the dog 15 extends horizontally through and is supported and guided in its movements by the 20 ends of the box or frame 27, the outer end of said body 22 being in an opening 34 in one end of said box or frame and the arms 23, 24 in openings 35, 36 in the other end of said box or frame. Within the slot 37 25 formed in the body 22 of the dog 15 is arranged a spring 38, one end of which is fastened to the box or frame 27 and the other end to the dog 15 and the purpose of which is to exert a normal tension against the dog 30 to pull it inwardly to its retracted position, whereby the dog when released to move will be automatically withdrawn inwardly or in 35 a direction toward the box 27.

35 The dog 15 will be adjusted horizontally to any suitable position to engage the log 11 and when so adjusted secured by means of a pin 39 mounted in the front of the box 27 and adapted at its inner end to enter any 40 one of the holes 25 in the dog. The pin 39 has at its outer end a head 40 and near its inner end a collar or shoulder 41. Between the shoulder 41 and the inner face of the front of the box 27, there is mounted on 45 the pin 39 a coiled spring 42, which has a normal tension acting to press the inner end of the pin toward the dog 15. When the inner end of the pin 39 is in a hole 25 of the dog 15, the latter becomes secured in its 50 adjusted position and can not be moved in either direction until said pin has been withdrawn therefrom. It is desirable under some circumstances that the dog 15 be locked against outward movement, such as 55 might be caused by the pull or tilting of the log against the prong 21, after the pin 39 has been withdrawn from the dog for purposes of readjustment or otherwise, and to this end I form the ratchet teeth 26 on the 60 arm 24 of the dog and provide a spring pawl 43 to engage said teeth, said pawl and teeth permitting the spring 38 when the dog is entirely released, to pull said dog inwardly to its retracted position, but preventing the 65 dog 15 from sliding or being pulled out-

wardly by the log after the withdrawal of the pin 39. When the dog 15 is being slid inwardly by the spring 38, the ratchet teeth 26 will ride by the pawl 43, but said pawl will prevent a reverse movement of the dog. 70 The pawl 43 is pivotally mounted on the end of the box 27, as shown in Fig. 5, and has pivotally connected with it one end of a pivoted lever-arm 44, whose other end is in the form of an eye encompassing the pin 39 75 adjacent to the head 40 of the latter, as shown in Figs. 5 and 6. When the pin 39 is moved inwardly and its inner end is entering one of the holes 25 in the dog 15, the head 40 on the pin will press against the adjacent end of the lever arm 44 and move it inwardly for the purpose of withdrawing the other end of said lever-arm outwardly and freeing the pawl 43 from the ratchet teeth 26, it being unnecessary when the dog 80 15 is secured by the pin 39 for the pawl 43 to be in engagement with the ratchet teeth 26. When the pin 39 is pulled outwardly from the dog 15, the pressure of the head 40 against the outer end of the lever-arm 44 85 will be released and then the spring dog 43 will automatically pass into engagement with the ratchet 26. I may, however, free both pin 39 and pawl 43 from the dog 15 by pulling outwardly on the pin and turning 90 the lever-arm 44 to withdraw the pawl 43 from the ratchet 26. I provide a small handle 45 on the lever-arm 44 for convenience in manually releasing the pawl 43 from the ratchet 26. 95

100 An important part of my invention pertains to mechanism for automatically stopping the movement of the knee 14 before the dog 15 has passed into the plane of the saw 16, mechanism for automatically releasing 105 the pin 39 from the dog and causing the pawl 43 to pass into engagement with said dog preparatory to the readjustment of the latter by the sawyer, and mechanism operable by the dog on its inward movement 110 under the action of the spring 38, to free the knee 14 from the means which stopped its movement.

115 The mechanism provided for stopping the knee in its movement toward the saw 16 comprises a hook 46 pivoted to the side of the knee 14, and a pin 47 extending laterally from the block 10 in position to be engaged by said hook during the travel of the knee toward the saw. When the hook 46 engages the pin 47 the knee will become locked against further movement toward the saw, and at such time the sawyer will know that it is time for him to readjust the dog 15. I provide means for automatically freeing the 120 hook 46 from the pin 47, and while this operation will be hereinafter described, I will at this place refer to the immediate devices connected with the hook for enabling its automatic release. The hook 46 is pro- 125 130

vided with a short upwardly extending crank arm 48, and to this arm is pivotally connected one end of a rod 49, whose other end is pivoted to a crank arm 50 carried by the lower end of a vertical pivotally mounted flat bar 51, the latter being held at its upper end in an arm 52 secured to the upper end of the knee 14 and at its lower end in a bearing 53 secured to or formed on the lower member of said knee. When the dog 15 is released and drawn inwardly by the spring 38, the inner end of its body 22 will strike the vertical bar 51 at one side of its axial line and cause said bar to turn, and the bar 51 thus set in motion will swing the crank arm 50 in a direction toward the saw 16 and thereby through the rod 49 and crank arm 48 turn the hook 46 upwardly from the pin 47, thus releasing the knee 14.

20 The means for automatically releasing the pin 39 from the dog 15 comprises three main parts, the first being the rod 54 (Fig. 6) having one end encompassing the pin 39 adjacent to that end of the lever 44 which is on said pin and having its body portion 55 normally extended through a bearing 56 on the box 27 and along the edge of the knee 14 and beyond said knee, there being a spring 57 on the rod 54 serving to normally project the body portion 55 of said rod beyond the edge of the knee. The second part of the said pin releasing mechanism comprises a vertical bar 58 hinged to the side of the knee 14 and carrying at its lower end a downwardly projecting arm 59. The bar 58 projects inwardly beyond the edge of the knee 14, as shown in Figs. 4, 5 and 6, so that said bar when moved in a direction toward the knee and box 27, will strike the projecting end of the rod 54 and press the same frontwardly against the stress of the spring 57. The bar 58 normally stands in the inclined position shown in Fig. 5 and is there yieldingly held by means of a spring 60. The hinges securing the bar 58 are such as to prevent the spring 60 from drawing the bar 58 outwardly from the knee beyond a suitably inclined position such as shown in Fig. 5. The third part of the pin releasing mechanism consists of a cam bar 61 (Fig. 2) secured to the side of the block 10 adjacent to the outer end of the latter. The arm 59 projecting downwardly from the bar 58 will, during the outward travel of the knee, be carried against the cam bar 61, and since the latter is designed for that purpose, the movement of said arm 59 along said bar will result in the arm acting to turn the bar 58 on its hinges in the direction toward the box 27 and rod 54, and this will occur when the knee 14 has reached a position at which the sawyer should adjust the dog 15. When the arm 59 is acted on by the cam 61 and the bar 58 is turned inwardly toward the box 27, said bar 58 will press against and drive the

rod 54 inwardly or to the front and toward the sawyer, and in doing so the end of said rod which is on the pin 39 will force said pin outwardly from the dog 15 and thereby effect the release of the dog so far as the pin 39 is concerned. The movement of the rod 54 to release the pin 39 also acts against the outer end of the lever 44 and rocks said lever in a direction to cause the pawl 43 to pass into engagement with the ratchet teeth 26. 70 The operation of automatically releasing the pin 39 from the dog 15 thus results in also applying the pawl 43 to the ratchet 26 so that the dog 15 will be held against moving outwardly under any force that may be applied to it, such as, for instance, the pull which the log itself, if inclined to tilt, might exert against said dog. 80

In the condition of the mechanism just described with the pin 39 free of the dog 15 and the pawl 43 in engagement with said dog, it will be the duty of the sawyer to readjust the dog, the knee 14 having traveled toward the saw 16 to the safe limit, and the sawyer will, therefore, first free the dog 15 90 from the log 11 and allow the spring 38 to retract the dog to its inward position, the dog at that time being entirely free to be acted on by said spring, and the sawyer will then again drive the prong of the dog into 95 the log and proceed with the sawing operation. The further movement of the knee and log toward the saw may be safely performed since at such time the dog is in its retracted position with its prong close to the 100 knee and to the edge of the log. During the final portion of the movement of the knee and log toward the saw the dog will be held by the pawl 43, since at such time the bar 58 still controlled by the cam 61, prevents the pin 39 from engaging the dog. 105

After the sawing has been completed the knee 14 will be redrawn to its normal position toward the right (looking at Fig. 1), and the bar 58 will thereby be removed from 110 the influence of the cam 61, so that it may be restored by the spring 60 to its normal outer position shown in Fig. 5. After the bar 58 has moved outwardly to its normal position the spring 57 and spring 42 will move the 115 rod 54 and pin 39 inwardly to their normal positions.

The operation of the features constituting my invention will be largely understood from the foregoing description, and 120 but brief further explanation is necessary.

The sawyer may readily, by means of the handle bar 31 and eccentric 30, adjust the box or frame 27 on the bar 28 and secure it in its adjusted position, and he may readily adjust the dog 15 horizontally to the required position and secure it by the pin 39. The point of the prong 21 of the dog 15 is driven into the log as usual, and thereupon the operation of sawing may be proceeded 130

with. As each section of the log is sawed off the sawyer will advance the knee and log, as usual, through the gear wheel 19 and rack 18. When during the use of the mill 5 the dog has sufficiently approached the saw to make its further movement in that direction unsafe, the bar 58 will be acted on by the cam 61 and free the pin 39 from the dog, and preferably immediately following 10 that step the hook 46 will engage the pin 47 and hold the knee against any further movement until after the dog has been reset. When the knee has been thus arrested by the hook, the sawyer will release the dog from 15 the log and allow the spring 38 to retract the dog toward the box or frame 27, and he will thereupon again force the dog into engagement with the log and proceed with the operation of the mill, the knee having become free, as hereinbefore explained, from 20 the hook 46 by turning upwardly from said hook under the thrust of the body portion 22 of the dog 15 against the bar 51.

My invention not only saves the time of 25 the sawyer, but prevents such accident as would follow from the dog passing into the path or plane of the saw.

I do not limit my invention to all of the details shown in the drawings, since I am 30 aware that these may be modified in several ways without departing from the invention.

I illustrate in Figs. 7, 8 and 9 one modified form of the invention in which I place the bar 70 (corresponding with the bar 58 35 of Fig. 5) at the front side of the knee 14 instead of on the opposite side thereof, and provide on the lower end of said bar 70 an inwardly projecting arm 71 to ride against an inclined or cam surface 72 provided on the block 10. In the arrangement 40 of the bar 70, arm 71, and cam 72 shown in Figs. 8 and 9, the pin 39 will be released by being pulled outwardly from the dog. The bar 70 will be set behind a collar 73 on the 45 pin 39 so that when the bar is moved outwardly by the cam it will press outwardly on the pin, with the same results attained by the bar 58 arranged as shown in Fig. 5. The bar 70 is hinged to the bar 28 of the 50 knee, as clearly shown in Figs. 8 and 9.

What I claim as my invention and desire to secure by Letters Patent, is:

1. In a saw-mill, a frame to be adjusted vertically on a knee of the mill, means for 55 securing said frame in its adjusted positions, a dog mounted to slide horizontally in said frame and adapted at its outer end to be driven into positive engagement with a log, separate means for positively securing the 60 dog in its relation to the log, and means for automatically releasing said dog-securing means from the dog without withdrawing the dog from the log when the knee reaches a definite position with relation to the saw; 65 substantially as set forth.

2. In a saw-mill, a frame to be adjusted vertically on a knee of the mill, means for 70 securing said frame in its adjusted positions, a dog mounted to slide horizontally in said frame and adapted at its outer end to be driven into positive engagement with a log, separate means for positively securing the 75 dog in its relation to the log, means for automatically releasing said dog-securing means from the dog without withdrawing the dog from the log when the knee reaches a definite position with relation to the saw, and means for thereafter automatically retracting the dog when the latter is manually freed from the log; substantially as set forth. 80

3. In a saw-mill, a dog for the knee, means for securing the dog in its relation to the log, means for automatically releasing said securing means from the dog when the knee reaches a definite position, means for automatically retracting the released dog when the latter is freed from the log, and means for engaging the dog after the release of the 85 said securing means therefrom to prevent the dog from being pulled outwardly by the log; substantially as set forth.

4. In a saw-mill, a dog for the knee, means for securing the dog in its relation to the log, means for automatically releasing said securing means from the dog when the knee 90 reaches a definite position, a spring for retracting the released dog when the latter is freed from the log, and pawl and ratchet mechanism for preventing the dog after its release from said securing means from being 95 pulled outwardly by the log; substantially 100 as set forth.

5. In a saw-mill, a frame to be adjusted vertically on a knee of the mill, means for 105 securing said frame in its adjusted positions, a dog mounted to slide horizontally in said frame and adapted at its outer end to be driven into positive engagement with a log, separate means for positively securing the dog in its relation to the log, and means for automatically releasing said dog-securing means from the dog without withdrawing the dog from the log when the knee reaches a definite position with relation to the saw, the means for releasing said dog-securing 110 means from the dog comprising a movable bar carried by the knee in operative connection with said securing means, and means on the block in the path of said bar for effecting its movement; substantially as set 115 forth.

6. In a saw-mill, a frame to be adjusted vertically on a knee of the mill, means for 120 securing said frame in its adjusted positions, a dog mounted to slide horizontally in said frame and adapted at its outer end to be driven into positive engagement with a log, separate means for positively securing the 125 dog in its relation to the log, and means for automatically releasing said dog-securing 130 means from the dog substantially as set forth.

ing means from the dog without withdrawing the dog from the log when the knee reaches a definite position with relation to the saw, the means for releasing said dog-
5 securing means from the dog comprising a pivoted bar carried by the knee in operative connection with said securing means, and a cam on the block against which a part of said bar is carried by the knee and which
10 moves said bar to effect the release of said securing means from the dog; substantially as set forth.

7. In a saw-mill, a frame mounted on the knee, a dog slideable therein, a spring connected with the dog for normally retracting it to its inner position, a pin for securing said dog in its adjusted position, and pawl and ratchet mechanism for holding the dog against outward movement when said pin
20 is released; substantially as set forth.

8. In a saw-mill, a frame mounted on the knee, a dog slideable therein, a spring connected with the dog for normally retracting it to its inner position, a pin for securing said dog in its adjusted position, pawl and ratchet mechanism for holding the dog against outward movement when the pin is released, and means for automatically releasing the pin from said dog when the knee
25 reaches a certain position; substantially as set forth.

9. In a saw-mill, a frame mounted on the knee, a dog slideable therein, a spring connected with the dog for normally retracting it to its inner position, a pin for securing said dog in its adjusted position, pawl and ratchet mechanism for holding the dog against outward movement when the pin is released, and means for automatically re-
30 leasing the pin from said dog when the knee reaches a certain position, said means comprising a movable member carried by the knee in operative connection with said pin and an obstruction on the block in the path
35 of said member for actuating it; substantially as set forth.

10. In a saw-mill, a frame mounted on the knee, a dog slideable therein, a spring connected with the dog for normally retract-
50 ing it to its inner position, a pin for securing said dog in its adjusted position, pawl and ratchet mechanism for holding the dog against outward movement when the pin is released, and means for automatically re-
55 leasing the pin from said dog when the knee reaches a certain position, said means comprising a pivoted member carried by the knee in operative connection with said pin and a cam on the block in the path of said

member for actuating it; substantially as set forth.

11. In a saw-mill, a dog for the knee, means for securing the dog in its relation to the log, means for automatically releasing said securing means from the dog when the knee reaches a definite position with relation to the saw, and means for then automatically engaging the dog to prevent its outward movement under the pull of the log; substantially as set forth.

70 12. In a saw-mill, a dog for the knee, means for securing the dog in its relation to the log, means for automatically releasing said securing means from the dog when the knee reaches a definite position with relation to the saw, and pawl and ratchet mechanism for then automatically holding the dog against outward movement; substantially as set forth.

75 13. In a saw-mill, a dog for the knee, means for securing the dog, means for automatically releasing said securing means when the knee reaches a definite position with relation to the saw, means for arresting the knee when it has traveled to a definite position, means for retracting the dog when it is released from the log, and means operable on the retraction of the dog for freeing said arresting means from the knee; substantially as set forth.

80 14. In a saw-mill, a dog for the knee, means for securing the dog, means for arresting the knee when it has traveled a safe distance toward the saw, and means operable from the retraction of the dog for freeing said arresting means from the knee; substantially as set forth.

85 15. In a saw-mill, a dog for the knee, means for securing the dog, means for automatically releasing said securing means when the knee reaches a definite position, means for then automatically engaging the dog to prevent its outward movement under the pull of the log, means for arresting the knee in a safe position, means for retracting the dog when it is released from the log, and means in the path of and operable by the retracting dog for freeing said arresting means from the knee; substantially as set forth.
